UNITED STATES PATENT OFFICE.

GEORGE A. MELLON, OF ST. LOUIS, MISSOURI.

DESIGN FOR WIRE FABRIC.

42,642.

Specification for Design.

Patented June 18, 1912.

Application filed December 7, 1911. Serial No. 664,497. Term of patent 14 years.

To all whom it may concern:

Be it known that I, GEORGE A. MELLON, a citizen of the United States, residing at St. Louis, in the State of Missouri, have invented a new, original, and ornamental Design for a Wire Fabric, of which the following is a specification, reference being had to the accompanying drawing, forming part thereof.

The figure is a plan view of a wire fabric, showing my new design.

I claim:

The ornamental design for a wire fabric, as shown.

GEORGE A. MELLON.

Witnesses:

FRED ARMSTRONG, Jr.,
MARIE BUDDE.
